S. P. JOHNSON

HOOK

Filed Dec. 30, 1922

Inventor

S. P. Johnson

By Watson E. Coleman
Attorney

UNITED STATES PATENT OFFICE.

SAMUEL P. JOHNSON, OF ETHELSVILLE, ALABAMA.

HOOK.

Application filed December 30, 1922. Serial No. 609,879.

To all whom it may concern:

Be it known that I, SAMUEL P. JOHNSON, a citizen of the United States, residing at Ethelsville, in the county of Pickens and State of Alabama, have invented certain new and useful Improvements in Hooks, of which the following is a specification, reference being had to the accompanying drawings.

10 This invention relates to certain improvements in hooks and it is an object of the invention to provide a novel and improved device of this general character especially designed and adapted for use in connecting a hook in a trace chain or the like to a singletree.

It is also an object of the invention to provide a device of this general character providing novel and improved means whereby the trace chain or the like can be readily disconnected from the hook and particularly in the event the trace chain is taut as when tangled up with the draft animal.

Another object of the invention is to provide a novel and improved device of this general character comprising a body member and a latch carried thereby the opposed faces of the body and latch having registering openings to provide an opening to receive a trace chain ring together with means for normally maintaining said latch and body in such relative arrangement.

The invention consist in the details of construction and in the combination and arrangement of the several parts of my improved hook whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in top plan of a hook constructed in accordance with a preferred embodiment of my invention;

50 Figure 2 is a view in side elevation of the hook as herein disclosed;

Figure 3 is a view in top plan of the body of the hook with a portion broken away and the spring applied, the latch being removed;

55 Figure 4 is a vertical sectional view taken

through a device as illustrated in Figure 1 with the portion of the pivot member of the latch in elevation; and

Figure 5 is a view in bottom plan of the latch as herein set forth.

As disclosed in the accompanying drawings, B denotes the body of my improved hook provided at one end portion with an opening 1 and through which is adapted to be directed a trace ring of a conventional type for connecting the body B to a singletree.

The opposite end portion of the body B is reduced from above in thickness to provide an extension 2, the upper face 3 of which being substantially flat. The opposite or lower face of the extension 2 is flush with the adjacent face of the body B and the thickness of the extension 2 as herein disclosed is equal to substantially one-half of the thickness of the body B proper.

The inner or upper surface of the extension 2 adjacent its outer or free end is provided thereacross with a recess 4 having the walls thereof opposed in a direction lengthwise of the body B rounded, with the outbows of said rounded portions opposed as is clearly illustrated in Figure 3 of the accompanying drawings.

The wall 5 provided in the body B above the extension 2 has at its central portion a substantially semi-circular recess 6 which is in continuation of a portion of the wall of the opening 7 disposed through both the body B proper and the extension 2 thereof. The lower portion of the wall 5 immediately adjacent the face 3 of the body B is undercut to provide a recess 8 open at its opposite end.

L denotes a latch member which when in closed position overlies the extension 2 in close contact with the face 3 thereof. The latch L has its lower or inner face provided with an outstanding pivot member or shank 9, said shank or member partially extending beyond the adjacent or inner end of the extension 2 and which extended portion is snugly received within the recess 6. The rear wall 10 of the latch L to one side of the member or shank 9 is substantially perpendicular to the longitudinal axis of the latch L while the wall 11 at the opposite side of the member or shank 9 is arranged slightly inwardly of the wall 10 and disposed on an outward

angle of approximately thirty degrees. When the portion 10 of the rear wall of the latch L is in contact with the adjacent portion of the shoulder 5 the movement of the latch L is limited in one direction with said latch L overlying the extension 2 of the body B. The arrangement of the wall 11 permits the latch L to have limited swinging movement relative to the body B and 10 to an extent to permit the desired engagement or disengagement of a trace ring between the latch L and the extension 2 of the body B.

The under surface of the latch L is provided with a transversely disposed recess 12 which is adapted to register with the recess 4 of the extension 2 to provide an opening through which is adapted to be directed a trace ring.

20 The inner or under surface of the latch L immediately adjacent to the member or shank 9 is provided with an arcuate recess 14 to receive portions of the coiled spring 15 encircling the member or shank 9, portions 25 of said spring being also received in the recess 8 hereinbefore referred to. One extremity of the spring 15 is angularly disposed as at 16 for contact with the portion 11 of the rear wall of the latch L, while the 30 opposite end portion of the spring 15 is provided with an angular extension 17 for contact with the adjacent portion of the wall 5. The spring 15 constantly urges the latch L into a position with the extension 2 and 35 to maintain said latch in such position.

In order that the latch L may have its full extent of swinging movement I find it of advantage to have the extension 17 of the spring 15 seat within a recess 18 produced in the portion 11 of the latch L.

40 With a hook constructed in accordance with an embodiment of my invention a trace ring or the like may be readily arranged with the openings afforded by the recesses 4 and 12 upon proper swinging movement of the latch L and said ring will normally be effectively held between said extension 2 and latch L.

When it is desired to release the trace ring 50 it is only necessary to swing the latch L into an open position and this movement of the latch can be accomplished partially irrespective of the strain imposed upon the trace such as being unduly taut when the 55 trace is tangled up with a draft animal.

The member or shank 9 is of a length to extend beyond the body B and disposed through said extended portion is a cotter pin 19 or the like which serves to maintain 60 the latch L in applied position with respect to the body B.

From the foregoing description it is thought to be obvious that a hook constructed in accordance with my invention is particularly well adapted for use by reason of 65 the convenience and facility with which it may be assembled and operated, and it will also be obvious that my invention is susceptible of some change and modification without departing from the principles and spirit 70 thereof and for this reason I do not wish to be understood as limiting myself to the precise arrangement and formation of the several parts herein shown in carrying out my invention in practice except as hereinafter 75 claimed.

I claim:

1. A hook of the class described, a body reduced in thickness to provide an extension, 80 said body and extension at the junction thereof being provided with an opening, a latch normally overlying the extension and provided with an integral pivot member extending through the opening, the end wall of the latch at one side of the pivot member 85 serving as a stop to limit movement of the latch member in one direction, the portion of the end wall of the latch member at opposite sides of the pivot member being on an angle to permit the latch member to have 90 limited outward swinging movement, and means for constantly urging the latch in the first direction and to maintain the latch in a position to overlie the extension, the opposite faces of the latch and extension being 95 provided thereacross with recesses normally registering to provide an opening.

2. A hook of the class described comprising 100 a body having an extension at one end of a thickness less than the thickness of the body, the body to one side of the extension having an end wall provided with a recess,

a latch normally overlying the extension, a laterally directed pivot member carried by the inner end of the latch and extending beyond said end, said extended portion of the pivot member being seated within the recess at the inner end wall of the body, and a spring member encircling the pivot member and coacting with the opposed end walls of the latch and body for normally maintaining the latch in a position overlying the extension of the body, opposed faces of the latch and body being provided with recesses 110 normally in register to provide an opening, the portions of the walls of the latch and the body adjacent the spring being recessed to receive portions of the spring.

In testimony whereof I hereunto affix my signature.

SAMUEL P. JOHNSON.
